UNITED STATES PATENT OFFICE.

LOUIS RONCA, OF JERSEY CITY, NEW JERSEY.

STEERING-WHEEL LOCK.

Application filed March 25, 1922. Serial No. 546,550.

To all whom it may concern:

Be it known that I, LOUIS RONCA, a resident of Jersey City, Hudson County, State of New Jersey, and a subject of the King of 5 Italy, have invented certain new and useful Improvements in Steering-Wheel Locks, of which the following is a specification.

This invention relates to improvements in locking devices for the steering wheels of 10 motor vehicles. One of the objects of my invention is to provide a locking mechanism to engage the spokes of a steering wheel operable by the combination method, that is to say, my improved lock does not need a 15 key to lock and unlock same, but is provided with means to lock and unlock the mechanism when manipulated in accordance with a number of selected numerals. One of the advantages of my improved lock is 20 that it can be fitted to a steering post housing when the wheel is removed from the steering post without the necessity of cutting the housing or in any way changing the steering mechanism.

25 I will now proceed to describe my invention in detail, the novel features of which I will point out in the appended claims, reference being had to the accompanying drawing, wherein:

30 Fig. 1 is a sectional view, partly in elevation, illustrating my improved lock as applied to a steering post;

Fig. 2 is a sectional detail view, the section being taken on a line 2-2 in Fig. 1, 35 the tumbler-disks being omitted;

Fig. 3 is a detail view, in elevation, of the fixed sleeve which forms part of the lock;

Fig. 4 is a sectional view, on line 4-4 40 Fig. 1, looking in the direction of the arrow, the spacing collar being omitted;

Fig. 5 is a view looking from the top in Fig. 4;

Fig. 6 is a detail view of one of the spacing collars looking from the top;

Fig. 7 is an enlarged fragmentary edge view of one of the tumbler disks;

Fig. 8 is a top plan view of the lowermost collar of the lock assembly; and

50 Fig. 9 is a view similar to Fig. 5, illustrating the indicated tumbler disk, as located in locking position.

My improved lock is comprised of a sleeve 10, which, when in use, is attached to the 55 steering post housing 11 of a steering mechanism; a slidable sleeve 12 mounted upon

fixed sleeve 10; a plurality of tumbler disks 13, 14 and 15; spacing collars 16 and 17; a locking dog 18 and a retaining collar 19 threaded on to the lower end of slidable 60 sleeve 12. The fixed sleeve 10 carries a key 10^a having spaced apart recesses or slots 20, 21 and 22 for the passage of teeth 23 carried by the disks 13, 14 and 15 which are spaced apart. Each disk 13, 14 and 15 is 65 slotted as at 24 for the passage of key 10^a, and each collar 16, 17 and 19 is slotted as at 25 for the same reason. Each collar 16, 17 and 19, in its upper surface, is provided with an annular channel 26 to receive the 70 teeth 23 carried by the tumbler disk. The under surface of dog 18 and collars 16 and 17 is provided with an annular channel 27 to receive a block 28 carried by each tumbler disk. In this instance, each disk carries 75 twelve teeth producing eleven spaces 29. Each disk is provided with twelve openings 30 to receive a pin 31 carried by block 28. In other words, block 28 can be moved to any opening 30 whereby the combination 80 can be changed at will. To align the slot 24 in any tumbler-disks, step by step movements are required, the number of steps being dependent upon the position of the block 28 relative to the slots 24 in the disk moved. 85 The step by step movements are detected by means of a spring 32 carried by each collar 16, 17 and 19 which contacts with the teeth 23, or more properly speaking, which enters the spaces 29 between the teeth. When a 90 tumbler is moved, the spring 32 adjacent thereto will spring into the spaces between the teeth, causing a slight click which can be felt by the manipulator of the disk. The lowermost collar 19 maintains the disks 13, 95 14, and 15 and spacing collars 16 and 17 assembled. When the mechanism is in locked position, as indicated in Fig. 1, the lower end of key 10^a will engage slot 25 in retaining collar 19; hence, said collar cannot be 100 removed from slidable sleeve 12. When the mechanism is in unlocked position, as indicated by dotted lines in Fig. 1, collar 19 can be removed for the purpose of changing the combination of the lock mechanism. 105 When the mechanism is in locked position, as indicated in Fig. 1, the lugs 18^a on dog 18 will engage the spokes 32 of the wheel carried by the steering post 33. In other words, the lugs 18^a will be positioned between the spokes of the wheel. When the lock is in unlocked position, the lugs 18^a 110

will be clear of the spokes 32, as indicated by dotted lines in Fig. 1.

When the device is locked, the slots 24 will be out of alinement with the key 10^a, as indicated in Fig. 9; hence, sleeve 12 cannot be moved longitudinally of the housing 11 to draw the lugs 18^a away from spokes 32. To move the sleeve 12 longitudinally of the housing 11, slots 24 in the disks must be alined with key 10^a, as indicated in Figs. 4 and 5. Should the device be locked, in which event slots 24 will be positioned away from key 10^a, and I desire to unlock same, I move each disk 13, 14 and 15 anti-clockwise until blocks 28 strike key 10^a, as indicated in Fig. 9. As the operator will know how many spaces the block carried by each disk is spaced away from the slot 24 therein, he will merely move each disk a number of steps equal to the number of spaces between the blocks and slots 24, the movement being clock-wise. The springs 32 will click off the steps. After each slot 24 has been alined with key 10^a, the sleeve 12 can be moved to draw lugs 18^a away from spokes 32. During the rotatory movement of disks 13, 14 and 15, teeth 23 will pass through slots 20, 21 and 22 in key 10^a, that is to say, when the device is in locked position. When the device is in unlocked position, the slot 24 will, of course, engage the key at the unslotted portion. The combination can be changed at any time by merely changing the position of blocks 28 relative to the slots 24. When the device is in locked position, the unslotted portion of each disk will engage its adjacent slot in key 10^a, thereby preventing the sleeve 12 from being moved; hence, said sleeve cannot be moved until slots 24 are alined with key 10^a, which requires knowledge of the combination.

What I desire to secure by Letters Patent is:—

1. In a steering wheel lock, a carrier arranged for securement to the housing of a steering post carrying a wheel, a key carried by the carrier having slots therein, a sleeve slideable longitudinally of the carrier, and disks rotatably mounted on the sleeve arranged to engage the slots in said key, each disk having a slot for the passage of the key,

teeth carried by each disk, a spring adjacent each disk to engage said teeth to cause clicks when the disks are rotated, and a stop carried by each disk to contact with the key, said stops being located in different positions relative to the slots in the disks and arranged to contact with said key in order that a starting point for the movement of the disks to carry out the combination will be provided.

2. In a steering wheel lock, a carrier arranged for securement to the housing of a steering post carrying a wheel, a key carried by the carrier having slots therein, a sleeve slideable longitudinally of the carrier, disks rotatably mounted on the sleeve arranged to engage the slots in said key, each disk having a slot for the passage of the key, teeth carried by each disk, a spring adjacent each disk to engage said teeth to cause clicks when the disks are rotated, and a stop carried by each disk to contact with the key, said stops being located in different positions relative to the slots in the disks and arranged to contact with said key in order that a starting point for the movement of the disks to carry out the combination will be provided, said stops being adjustably mounted on their respective disks in order that the combination can be changed.

3. In a steering wheel lock, a carrier arranged for securement to the housing of a steering post carrying a wheel, a key carried by the carrier having slots therein a sleeve slideable longitudinally of the carrier, disks rotatably mounted on the sleeve arranged to engage the slots in said key, each disk having a slot for the passage of the key, teeth carried by each disk, a spring adjacent each disk to engage said teeth to cause clicks when the disks are rotated, a stop carried by each disk to contact with the key, said stops being located in different positions relative to the slots in the disks and arranged to contact with said key in order that a starting point for the movement of the disks to carry out the combination will be provided, and means carried by the slideable sleeve to engage the spokes of a steering wheel.

LOUIS RONCA.
